RING BINDER MECHANISM

Frank Stanley Schade, Holyoke, Mass., assignor
to National Blank Book Company, Holyoke,
Mass., a corporation of Massachusetts

Application August 10, 1943, Serial No. 498,056

3 Claims. (Cl. T29—24)

This invention relates to loose leaf binders and more particularly to the mechanism by which the leaves are releasably held in the binder.

The principal object of the invention is the provision of a simplified mechanism of sturdy construction, the parts of which may, if desired, be formed of wood, plastics, and similar non-metallic materials. A further object is to secure economies in manufacture of the parts and in their assembly.

Other and further objects residing in the details of the structure will be made apparent in the following specification and claims.

In the accompanying drawing—

Fig. 1 is a plan view of one embodiment of the invention, parts of the case being broken away;

Fig. 2 is an end elevational view of the structure shown in Fig. 1;

Fig. 3 is a sectional view substantially on line 3—3 of Fig. 1 showing the parts in ring-closing position;

Fig. 4 is a sectional view substantially on line 4—4 of Fig. 1, the ring being shown closed;

Fig. 5 is a view similar to Fig. 3 but with the parts shown in ring-opening position;

Fig. 6 is a sectional view substantially on line 6—6 of Fig. 1, the parts being shown in ring-opening position;

Fig. 7 is a sectional view substantially on line 7—7 of Fig. 6, showing a detail of the ring hinge;

Fig. 8 is a view similar to that of Fig. 5, but showing a modified form; and

Fig. 9 is a sectional view substantially on line 9—9 of Fig. 8.

Referring to the drawing, the binder case is made up of front and rear cover members 10 hinged to a back panel 11, to which the ring binder mechanism generally indicated at 12 is secured, as by rivets 13.

The binder mechanism comprises a supporting or base member 14 which may be formed of wood, plastic, or other suitable material. Member 14 is formed with a central groove 15 in which a locking or ring actuating bar 16 is slidably mounted. Bar 16 is held in groove 15 by pins 17 extending transversely of groove 15 and through slots 18 formed in bar 16. The engagement of pins 17 with the ends of slots 18 limits the sliding movement of the bar in the groove.

The binder rings 20 are split, the halves being hinged together at 19 to permit the rings to be opened to receive the loose leaf sheets which the binder is to accommodate. The rings 20 may be formed of plastic and, as best shown in Fig. 7, each ring half is formed with a hub member 21,

through which a pintle 22 extends to complete the hinge of the ring. The free ends of the ring halves are preferably provided respectively with a pin 23 and a socket 24 which maintain the ring halves in alignment when the ring is closed. The rings are seated in transverse grooves 25 formed in member 14, and the longitudinal groove 15 is enlarged as at 26 adjacent the transverse grooves to accommodate the hubs 21 of the rings. The ends 31 of the grooves 25 are elevated above the center portion and engage the ring halves less than 90° from the hinge, so that the ends of the groove press the ring halves closed when the rings are wedged downwardly between them.

The under edge of bar 16 is cut away adjacent each ring, as shown in Figs. 3 to 6 inclusive, to form edge portions 27 and 28 at different elevations from the bottom of the groove 15, the portions 27 and 28 being connected together by and are extensions of an inclined cam edge 29. When the rings are closed in normal binding position, the bar 16 is positioned as shown in Figs. 3 and 4, with edge portion 27 engaging the inner circumference of the ring substantially at the hinge, to hold the ring wedged between the ends 31 of the groove 25, thereby maintaining the ring closed. The bottom 30 of groove 25 is shown substantially concentric with the closed ring, but the ends of the groove 25 are the essential points of support.

When it is desired to open the rings for the removal or insertion of filler sheets, the bar 16 is slid in groove 15 to the position shown in Figs. 5 and 6, so that edge portion 28 overlies the hinge of the ring. In this position the ring halves may be separated, the edges 31 of the transverse grooves acting as fulcrums for the ring halves as the ring hinge moves radially inward in the opening operation until the hinge engages the edge portion 28, which limits the opening movement of the ring halves. The rings are thus simultaneously released and may be simultaneously opened by pulling outwardly on the spread leaves of the filler sheets mounted on the rings, or the rings may be opened individually by grasping the ring halves with the fingers.

As will be evident from Fig. 5, when bar 16 is shifted to the right in that figure, the end of the adjacent hub 21 will be engaged by the inclined cam edge 29 which will force the hinge downwardly to close the ring halves about the wedging fulcrums 31 and return the rings to closed and seated position, as in Figs. 3 and 4.

Preferably, the ends of hubs 21 are slightly

beveled, as indicated at 32, to facilitate the operation of cam 29 in depressing the ring hinge.

For convenience in manipulating the bar 16, the body portion 14 is preferably cut away at its ends, as indicated at 33.

In Figs. 8 and 9 the structure previously described is modified by the addition of means for positively opening the rings by movement of the bar 16 to the position shown in Fig. 5. In Figs. 8 and 9 the parts are shown in the position they occupy just prior to completion of the opening movement, in order to better show the relation of the parts. In general the modification includes the addition to bar 16 of a cam 35 at each ring position for elevating the ring hinges, and the provision of upper fulcrums 36 about which the ring halves are swung to open position as the hinge is raised.

The cam 35 is formed on projection 37 carried by bar 16, and the fulcrums 36 are provided by the outer edges of members 38 secured in the upper portion of transverse grooves 25, as shown in Fig. 9.

As will be evident from Figs. 8 and 9, when bar 16 is moved in the direction of the arrow in Fig. 8, cam 35 engages beneath hubs 21 as soon as the latter are free of edge 27. On continued movement of the bar 16 hubs 21 ride up the inclined surface of cam 35, elevating the hinge. As the hinge rises, the ring halves engage fulcrums 36, as indicated in Fig. 9, and continued elevation of the hinges causes the ring halves to swing to open position about the fulcrums. On the return movement of bar 16 the cam 29 depresses the hinge to swing the ring halves closed about lower fulcrums 31, as previously described.

What I claim is:

1. A ring binder mechanism comprising, a plurality of split hinged rings, a support therefor provided with transverse grooves in which the rings are respectively mounted, the ends of the grooves forming spaced supporting members engaging the outer circumference of the rings on opposite sides of the ring hinges at points less than 90° from the hinges, means retaining the rings in the grooves and means engaging the inner circumference of the rings, substantially at the hinge, for wedging the rings between said spaced supporting members to maintain the free

ends of the ring halves in ring closing engagement, said last-named means being movable to release the hinges and permit the ring halves to swing outwardly about said spaced supporting members to open the rings.

2. A ring binder mechanism comprising, a plurality of split hinged rings, a support therefor provided with transverse grooves in which the rings are respectively mounted, the ends of the grooves forming spaced supporting members engaging the outer circumference of the rings on opposite sides of the ring hinges at points less than 90° from the hinges, means retaining the rings in the grooves, a bar mounted on the support and extending through the rings, and cams carried by the bar and engaging the inner circumference of the rings, substantially at the hinges, for wedging the rings between said spaced supporting members to maintain the free ends of the ring halves in ring-closing engagement, said bar being slideable on the support to release the hinges from the cams and permit the ring halves to swing outwardly about said spaced supporting members to open the rings.

3. A ring binder mechanism comprising an elongated support having a groove extending longitudinally thereof, spaced grooves extending transversely of the support and intersecting the longitudinal groove, a split hinged ring positioned in each transverse groove with the hinge of the ring at the intersection of the transverse groove and the longitudinal groove, the ends of the transverse grooves forming spaced supporting members engaging the outer circumference of the rings on opposite sides of the ring hinges at points less than 90° from the hinges, a bar mounted in the longitudinal groove and extending through the rings to retain the latter in the transverse grooves, and cams carried by the bar and engaging the inner circumference of the rings, substantially at the hinges, for wedging the rings between said spaced supporting members to maintain the free ends of the ring halves in ring-closing engagement, said bar being slideable in the groove to release the hinges from the cams and permit the ring halves to swing outwardly about said spaced supporting members to open the rings.
